UNITED STATES PATENT OFFICE.

HENRY F. CAUSEBROOK, OF GREENFIELD, MASSACHUSETTS.

ELECTRICAL CONDENSER.

1,415,220.

Specification of Letters Patent.

Patented May 9, 1922.

Application filed June 18, 1921. Serial No. 478,553.

To all whom it may concern:

Be it known that I, HENRY F. CAUSEBROOK, a citizen of the United States of America, residing at Greenfield, in the county of Franklin and Commonwealth of Massachusetts, have invented certain new and useful Improvements in Electrical Condensers, of which the following is a specification.

10 This invention relates to improvements in the construction of electrical condensers.

An object of the invention is to so construct an electrical condenser that it may be as free from imperfections or fracture as 15 possible, when it is completed.

A further object is to improve the present method of constructing such condensers, whereby they may be readily formed of any suitable size, and at the same time produce 20 an article that is preferably rectangular in shape.

Heretofore it has been a common practice to first form the condenser by rolling together a strip of dielectric material (as 25 paper) and a strip of conducting material (as tinfoil). This practice has been found to be objectionable for the reason that when the roll is completed and subjected to pressure to produce a more or less rectangular 30 shaped article, the dielectric and conducting materials are often embedded in each other, thus destroying or materially lessening the usefulness. The finished condenser is often broken or fractured and often times both 35 the insulating and electric conducting material are injured or broken. This practice, moreover, is further objectionable in that it can not be repaired.

It has also been a common practice to 40 construct condensers by forming or building them up with alternate layers of insulating material and tinfoil. This practice is objectionable because after the condenser is subjected to the usual final treatment of pressure 45 sure and baking it cannot afterwards be taken apart and repaired.

In the present improvement, these objections are in a large measure overcome, both as to defects in the finished article, 50 and difficulty in locating and repairing the condenser.

These and other objects will appear in the body of the specification and will be particularly pointed out in the claims.

Referring to the drawings:

Fig. 1 is an end elevational view showing the condenser in the process of construction, with the strip of dielectric material partially folded together in opposite directions to form pockets to receive the pieces of tinfoil.

Fig. 2 is a sectional view on the line 2—2 of Fig. 3.

Fig. 3 is a perspective view showing in outline the finished condenser.

Fig. 4 is a detail view of one of the pieces 65 of tinfoil.

Fig. 5 is a perspective view similar to Fig. 1 prior to folding the elements together.

Fig. 6 shows the tinfoil applied before the 70 strip is folded.

Referring to the drawings in detail: 1 designates a continuous strip of suitable insulating or dielectric material, as paper coated with some suitable material, which is folded or bent in opposite directions by any 75 suitable means, as shown, at suitably spaced distances along its length. These folds or bends are indicated at 2, 3, 4, 5, etc. The intermediate portions of the strip between the folds are indicated by the reference 80 numerals 6, 7, 8, 9, 10, etc. These partially folded portions of the strip serve to form V-shaped pockets 11, 12, 13, 14, 15, etc., to permit the ready insertion of the pieces of 85 conducting material.

The strip 1 may, if desired, have the pieces of conducting material, indicated at 16, 17, 18, 19, 20, etc., applied thereto by any suitable means before it is folded, or these pieces of tinfoil may be inserted in the pockets 11, 12, 13, 14, and 15 after it is partially folded, as shown in Fig. 1. Any suitable adhesive is employed to cause the pieces of tinfoil to readily adhere to the opposite sides of the strip 1, and either before or after the folding 95 operation, as desired. In any instance, however, the pieces of tinfoil are encased within a pocket like compartment or receptacle which is produced after the folding operation.

After a suitable length of insulating strip and pieces of tinfoil have been assembled,

the whole is then folded into the compact rectangular form shown in Fig. 3, and in cross-section in Fig. 2.

Fig. 5 shows in perspective the assembled strip of insulating material and the pieces of tinfoil in contact with the portions intermediate the bends or turns 2, 3, 4, 5, etc., prior to the operation of folding the whole into the finished condenser shown in Fig. 3.

10 An important feature of the present invention is in thoroughly insulating the inner ends or the portions of the individual pieces of tinfoil which engages or is close to the bends 2, 3, 4, and 5 by having the strips of 15 insulating material bent or folded around these inner ends or edges as indicated at the points 2, 3, 4, and 5, thereby thoroughly preventing the charge from creeping or 20 jumping across the inner edges of the pieces of tinfoil. This feature is clearly shown in Fig. 2.

Another important feature is in permitting the finished condenser to be readily opened or unfolded, as shown in Fig. 5, 25 should a defect or break occur in any portion of its length. After it has been opened or extended for inspection it can then be very readily repaired by anyone skilled in the art.

30 It will also be observed that the outer edges of the pieces of tinfoil extend in opposite directions, whereby electrical connection may be very readily made with these edges when the condenser is in use.

35 The folded strip will closely engage the opposite surfaces of the tinfoil pieces, as shown in Figs. 2 and 3. The final step in the process of forming the condenser is to close or push the pockets together and thereby 40 encase the pieces of conducting material which are inserted in the pockets. The final shape of the condenser is shown in dotted outline in Fig. 3, by the lines 21, 22, and 23.

What I claim is:

45 1. An electric condenser, comprising a continuous strip of dielectric material formed with bends or folds therein along its length to form pocket-like receptacles, an individual piece of electric conducting material in each pocket and on opposite sides

of the strip and extending from one bend or fold to the next bend or fold of the strip, the outer ends of the pieces projecting beyond the bends or folds to form terminals.

2. An electric condenser, comprising a 55 continuous strip of dielectric material formed with bends along its length to form pocket-like receptacles, an individual piece of electric conducting material in each of said pockets and on opposite sides of the 60 strip, the piece having one of its ends engaging or close to a bend and its outer end projecting beyond two adjacent bends to form terminals, said bent strip being closely in contact with the opposite sides of said pieces. 65

3. An electrical condenser comprising a single strip of folded insulated material and a single or individual piece of electrical conducting material between the adjacent folds and projecting from opposite edges 70 of the folded strip.

4. The method or process of constructing an electric condenser, which consists in applying individual pieces of conducting material to the opposite sides of a single strip 75 of insulating material and after the application of such pieces folding the strip in opposite directions to form substantially closed pocket-like receptacles for encasing the conducting material between the folds of the 80 strip.

5. An electrical condenser having its dielectric material consisting of a single strip that is folded in opposite directions along its length to form pockets to receive the conducting material, said conducting material comprising individual pieces and said strip being folded around one end of the pieces of conducting material and against the opposite sides of the same and the opposite 90 ends of the conducting material projecting in opposite directions and beyond the folded or bent portions of the strip as described.

6. A folded condenser comprising a single strip of dielectric material to form 95 pocket-like receptacles and individual pieces of electric conducting material in said receptacles and projecting beyond the opposite sides of the finished article.

HENRY F. CAUSEBROOK
